UNITED STATES PATENT OFFICE

FRANK JAMES CANTRELL, OF SAN FRANCISCO, CALIFORNIA

DESIGN FOR A PIN OR SIMILAR ARTICLE

Application filed August 13, 1929. Serial No. 32,403. Term of patent 7 years.

To all whom it may concern:

Be it known that I, FRANK JAMES CANTRELL, a citizen of the United States, residing at San Francisco, in the county of San Francisco and State of California, have invented a new, original, and ornamental Design for Pins or Similar Articles, of which the following is a specification, reference being had to the accompanying drawing, forming part thereof.

I claim:

The ornamental design for a pin or similar article, as shown.

FRANK JAMES CANTRELL,
